SUBSURFACE HYDRAULIC PUMP

Duane E. Marquis, Bartlesville, Okla., assignor to Phillips Petroleum Company, a corporation of Delaware

Filed Jan. 2, 1959, Ser. No. 784,800

9 Claims. (Cl. 121—158)

This invention relates to a subsurface hydraulic pump, such as that used in pumping oil or other deep wells. In another aspect, it relates to a fluid-actuated subsurface hydraulic pump the reciprocating engine of which is controlled by a novel fluid-actuated reversing valve. In another aspect, it relates to a reversing valve for a fluid-actuated reciprocating engine.

In producing oil from deep wells, a common method of production involves the use of a hydraulic subsurface pump. This type of pump is actuated by fluid pressure in the form of power oil supplied from the surface to operate a hydraulic engine in the well which in turn actuates a displacement pump, the produced oil being pumped to the surface along with exhausted power oil. The engines used are reciprocating engines and must of necessity have reversing or directional valves to change the direction of the engine piston when the latter reaches the ends of its strokes. Many of the prior art subsurface hydraulic pumps rely on mechanical tripping devices, such as springs, trip rods, push rods, and the like to reverse or change the direction of the engine piston. Such mechanical tripping devices are often unreliable in that the mechanically tripped reversing or directional valve often stalls at dead center or at a no-start position. As a result, in order to remedy this situation, it is often necessary to pull the hydraulic pump from the well, disassemble the same and repair the tripping mechanism. In addition, in the operation of many of these prior art hydraulic pumps the power oil input pressure acts on a piston area smaller than that of the production plunger, thereby making it impossible to vary the engine and pump areas to gain hydraulic ratio advantage. Many of these mechanically tripped reversing valves are dependent upon the stroke length of the pump, thereby placing limitations on the design of the engine and pump pistons.

Accordingly, an object of this invention is to provide an improved subsurface hydraulic pump. Another object is to provide a fluid-actuated subsurface hydraulic pump, the reciprocating engine of which is controlled by a novel fluid-actuated reversing or directional valve. Another object is to provide an improved reversing valve for a fluid-actuated reciprocating engine. Another object is to provide a reversing valve for a fluid-actuated engine, which valve is independent of the stroke length of the pump. Another object is to provide a reversing valve for a fluid-actuated reciprocating engine, which valve is not susceptible to the stalling, dead-center, and no-start disadvantages associated with mechanical tripping devices. Another object is to provide a reversing valve which is independent of the hydraulic engine and displacement pump so that the hydraulic ratio advantage can be obtained. Other objects and advantages of this invention will become apparent to those skilled in the art from the following discussion, appended claims, and accompanying drawing in which:

Figure 1 is an elevational view, shown partly in section, of a single zone producing well having the pro-

2

duction unit or subsurface hydraulic pump of this invention installed therein;

Figure 2 is a detailed sectional view of the subsurface hydraulic pump of this invention;

Figure 3 is an enlarged sectional view, showing a portion of Figure 2 in detail, in particular the reversing valve when the latter is in its downstroke position;

Figure 4 is a view similar to Figure 3 illustrating the reversing valve in its upstroke position; and

Figures 5 and 6 are cross-sectional views of Figure 4 taken along the planes indicated.

Referring now to the drawing in detail, wherein like parts have been designated with like reference numbers, and to Figure 1 in particular, there is shown a borehole

15 having a casing string 11 therein, the lower end of which is provided with spaced perforation 12 adjacent an oil producing formation 13. A casing head 14 is attached in a conventional manner to the upper end of casing string 11. Depending within casing string 11 is 20 a power oil tubing string 16, the upper end of which extends through casing head 14 and is provided with a conventional cap 17. The lower end of tubing 16 terminates in a shoe assembly 18 to which is attached a small string of production-exhaust power oil tubing 19, often 25 referred to as a macaroni string, the upper end of the latter extending through casing head 14. The annular space 21 between casing 11 and tubing strings 16, 19 communicates at its upper end with a surface pipe 22, having a valve therein, for the withdrawal of any gas 30 accumulating within the upper end of annular space 21. The upper end of tubing string 16 communicates at the surface with a power oil supply pipe 23 having a valve 24 therein, this pipe being in communication with the outlet of a pump 26 which in turn communicates via pipe 35 with the upper end of an oil-water separator 28. The upper end of the macaroni tubing string 19 communicates at the surface with a production-exhaust power oil pipe 29 having a valve 31 therein, this line communicating with an extension 32 which in turn communicates with 40 oil-water separator 28 near the middle thereof. Surface pipe 33 communicates at one end with power oil supply pipe 23, downstream of pump 26, and communicates at its other end with the production-exhaust power oil pipe 29 at a point upstream of valve 31, pipe 33 having a valve 34 therein. Surface pipe 36 communicates at one end with power oil supply pipe 23 and communicates at the other end with pipe 32, pipe 36 having a valve 37 therein. Oil is withdrawn from the upper end of oil-water separator 28 and conveyed via line 38 to an oil storage 50 tank 39.

Referring now to Figure 2, wherein the subsurface hydraulic pump of this invention is illustrated in detail, the lower end of power oil tubing 16 is threadedly secured to a tubing extension 15 by means of collar 41.

55 Tubing extension 15 houses the improved subsurface hydraulic pump of this invention, this pump being generally designated 42 in the drawing. The upper end of the hydraulic pump 42 is provided with a conventional fishing neck 43 and a conventional flexible packer cup 44, shown in its relaxed position, which is held in place by a lock nut 46. The lower end of fishing neck 43 is threadedly fixed to a top pump plug 47 which has an outer diameter slightly smaller than the inner diameter of collar 41, a pump seal 48, such as an O-ring, being interposed therebetween to seal the upper power oil supply passage 49 from the annular space 51 between tubing extension 15 and the production unit 42. A cylindrical housing member 52 is threadedly secured at its upper end to the lower periphery of pump plug 47, said housing terminating at 60 its lower end in a bottom pump plug 53. The latter is provided with a tapered nose portion 54 which is adapted to seat in the upper end of a tubing standing valve hous- 65 70

ing 56. The latter is rigidly disposed within a pump inlet passage 57 in shoe assembly 18, the pump inlet passage being in communication with the oil which accumulates in the lower end of the casing 11. Standing valve housing 56 is provided with the usual ball valve 58 and stop or cage 59, this standing valve preventing flow of fluid from the interior of tubing extension 15 to the exterior thereof, but allowing the flow of oil from the exterior of tubing extension 15 to the interior thereof via the inlet passage 61 of the standing valve. The bottom pump plug 53 is similarly provided with a standing valve, the latter comprising an inlet passage 62, which communicates with inlet passage 61, and the usual ball valve 63 and stop 64, the standing valve in the bottom pump plug similarly permitting only upward flow of oil from the exterior of the pumping unit 42 to the interior thereof. The lower end of macaroni string 19 is secured to the shoe assembly 18 and communicates at its lower end with a passage 66 that in turn communicates with the interior of tubing extension 15 and annular space 51.

When it is desired to produce the oil from formation 13, tubing string 16 and macaroni string 19 are inserted within casing 11 and the pumping unit 42 is introduced into the upper end of tubing string 16 and allowed to fall therewith until it comes to rest at the lower end of the tubing string 16, the tapered nose 54 of the bottom pump plug 53 seating on the standing valve housing 56 of the shoe assembly 18. When it is desired to remove the pumping unit 42 from the well, for example after completing the production of the oil zone 13 or to make minor repairs, this can be accomplished by pumping power oil down macaroni string 19 and up annular space 51, the resulting pressure acting on seal 48 causing the release of the production unit 42 and then causing the expansion of the packer cup 44, which results in the production unit 42 being pushed upwardly through tubing 16 to the surface.

Housing 52 is divided by a partition 67 into an engine chamber 68 and a displacement chamber 69. The upper and lower portions of engine chamber 68 have reduced diameter portions in the form of dashpot chambers 70, 71, respectively. Slidably disposed within engine chamber 68 is an engine piston 72, the top and bottom portions of which have reduced outer diameters slightly smaller than dashpot chambers 70, 71, respectively. Slidably disposed within pump chamber 69 is a displacement piston 73. Engine piston 72 and displacement piston 73 are rigidly connected together by means of a connecting rod 74 which passes through an opening 76 in partition 67, a positive seal being effected between engine chamber 68 and pump chamber 69 by means of suitable packing 77. Displacement piston 73 is provided with a traveling valve comprising ball valve 78 and passages 79, 81. Ball valve 78 is adapted to seat on a shoulder within passage 81, the latter communicating with the lower portion of pump chamber 69 and passage 79 communicating with the upper portion of pump chamber 69.

Pump chamber 69 communicates at its upper end with annular space 51 via transverse bores 82. If desired, the lower end of housing 52 adjacent pump chamber 69 can be provided with a plurality of vertical passages 83 which communicate at their lower end with annular space 51 via bores 84.

Disposed within the upper portion of the production unit 52 is the novel reversing or directional valve of this invention, which valve is schematically shown in Figure 2 and generally designated 86. The upper end of engine chamber 68 communicates with reversing valve 86 via axial passage 87. The lower end of engine chamber 68 communicates with transverse bores 88 in partition 67, these bores communicating in turn with a plurality of vertical bores 89 which communicate at their upper ends with reversing valve 86. Reversing valve 86 communicates with annular space 51 via transverse bore 91 in top pump plug 47 and reversing valve 86 communicates with

the power oil supply passage 49 of tubing string 16 via passage 92 in top pump plug 47 and fishing neck 43.

Referring now to Figures 3 to 6 of the drawing, reversing valve 86 comprises a reversing valve housing 93 the upper end of which is threadedly secured to the periphery of top plug 94 and the lower end of which is secured and closed by a bottom plug 96. Disposed within reversing valve housing 93 is a main or directional valve housing 97 and disposed within the lower portion of the reversing valve housing 93 is a pilot valve housing 98. Main valve housing 97 is provided with a central main valve chamber 99 in which is vertically and slidably disposed a cylindrical main valve member 101, the latter being provided with enlarged portions 101a, b, and c having diameters slightly smaller than that of chamber 99. Similarly, pilot valve housing 98 is centrally provided with a pilot valve chamber 102 in which is vertically and slidably disposed a pilot valve member 103. The upper end of the main valve chamber 99 has a reduced diameter 104 and the upper end of pilot valve chamber 102 is similarly provided with a reduced diameter 106.

Main valve housing 97 is provided with a plurality of transverse bores 107, 108, 109, 111, and 112 which communicate at their inner ends with the central part of the main valve chamber 99. The upper end of the reduced main valve chamber 104 communicates with a passage 113 in plug 94 which in turn communicates via vertical bores 115 with the annular space 116 between the production housing 52 and the reversing valve housing 93, passage 113 also communicating via bores 115 with an annular space 114 in pump plug 47, which space in turn communicates with the power oil supply passage 92.

The outer ends of transverse bore 107 communicate with the annular space 117 between the reversing valve housing 93 and the upper portion of main valve housing 97. The upper end of annular space 117 communicates via bores 90 in top plug 94 with exhaust power oil passage 91 in pump plug 47. A transverse bore 107 also communicates with the vertical bore 118 in the main valve housing 97. The outer end of transverse bore 108 communicates with a vertical bore 119 in the main valve housing 97. The outer ends of transverse bores 109 communicate with annular space 116 via a plurality of openings 121 in the reversing valve housing 93. The outer ends of transverse bores 111 communicate with the annular space 122 between the lower portion of the main valve housing 97 and the reversing valve housing 93. The outer end of transverse bore 112 also communicates with the vertical passage 118 in the main valve housing 97.

The upper reduced portion 106 of the pilot valve chamber 102 communicates at its upper end with transverse bore 120, and portion 106 communicates at its middle with the inner ends of a plurality of transverse bores 123, 124, and 125. Bore 120 communicates at its outer end with the lower end of vertical bore 119. Communication between the inner ends of bores 124 and 125 is obtained via annular groove 126 in the upper portion of pilot valve 103 when the latter is in its lower position, as shown in Figure 3. Similarly, communication between the inner ends of transverse bores 123 and 124 is obtained via the annular groove 126 when the pilot valve 103 is in its upper position, as shown in Figure 4. The lower portion of main valve chamber 99 communicates with a bore 127 in the upper end of the pilot valve housing 98, passage 127 communicating at its lower end with transverse bore 124. The outer end of transverse bore 123 communicates with the lower end of the vertical passage 118 which extends from the main valve housing 97 into the upper end of the pilot valve housing 98. Similarly, the outer end of the transverse bore 125 communicates via vertical bore 135 and inlet 128 with the annular passage 116 between the production unit housing 52 and the reversing valve housing 93. Communication between the annular space 122, formed between the lower portion of the main valve housing 97 and the

reversing valve housing 93, with the annular space 131, formed between the lower portion of the pilot valve housing 98 and reversing valve housing 93, is had by passages 132 formed in the upper end of the pilot valve housing 98. Annular space 131 communicates in turn with the lower enlarged portion 130 of the pilot valve chamber 102 via passages 133 formed in the central portion of the pilot valve housing 98.

The lower end of pilot valve 103 is provided with a piston 134 which is slidably disposed within the enlarged lower end 130 of the pilot valve chamber 102, the periphery of piston 135 being provided with conventional piston rings. The lower face of the piston 134 is provided with an orifice plug 136 having an orifice 137 of predetermined size therein which communicates via passages 138 with the upper end of the enlarged portion 130 of the pilot valve chamber 102.

Certain of the communicating passages, spaces, inlets, and outlets described hereinbefore, such as bore 109, inlets 121, and annular spaces 117, 122 are sealed off with sealing rings, such as O-rings, but for purposes of brevity, these have not been described although they are shown in the drawing.

In operation, power oil, or other hydraulic liquid, is pumped from tank 28 at the surface via pipes 27 and 23 into the upper end of the production tubing 16, the power oil supply flowing down the tubing passage 49 to the lower end thereof. To accomplish this normal supply of power oil, valves 24 and 31 are opened, and valves 34 and 37 are closed. Power oil is thus introduced into the production unit 42 at the upper end thereof through inlet passage 92. The power oil from inlet 92 flows into the annular passage 114, Figure 3, in the pump plug 47 and then flows downwardly via bores 115 into the annular space 116 between the production unit housing 52 and reversing valve housing 93, this power oil being introduced via main valve inlets 121 into the main valve housing 97. From inlets 121, the power oil enters the central portion of the main valve chamber 99 via lateral bores 109.

On the downstroke, power oil supplied via lateral bores 109 to the central portion of the main valve chamber 99 flows from the main valve chamber via lateral bores 111 into the annular space 122 surrounding the lower end of the main valve housing 97 and the upper end of the pilot valve housing 98. The power oil from the annular space 122 then flows via passages 132 into the annular space 131 and via passages 133 into the upper end of the enlarged portion 130 of the pilot valve chamber 102. The power oil then passes through passages 138 in the piston 134 and flows at a predetermined rate through orifice 137 into engine inlet 87, and then into the dash pot enlargement 70 of the engine chamber 68.

Fluid pressure from the power oil is also supplied to the upper end of the main valve chamber 99 from the annular chamber 114 via passage 113, this fluid pressure being applied to the upper end of the main valve member 101.

The power oil in annular space 116 also enters the pilot valve housing 98 via inlet 128, the power oil thus introduced flowing via vertical bore 135 into the lateral bore 125, and then passing via the annular groove 126 formed in the upper end of pilot valve member 130 into the lateral bore 124. From the latter, the power oil is supplied via passage 127 into the lower end of main valve chamber 99.

The fluid entering the upper end of the engine chamber 68, Figure 2, causes the engine piston 72 to move downwardly, this movement being translated to the displacement piston 73 by reason of connecting rod 74. On moving downwardly, the engine piston 72 displaces the oil in the lower portion of the engine chamber 68 via lateral bores 88 in the partition 67 separating the engine chamber 68 and pump chamber 69. From lateral bores

88, the exhausted oil flows upwardly in the communicating annular spaces 89 and 116, and thence into inlets 121.

Exhaust power oil from below engine piston 72 travels via bores 88, 89 to mingle with primary power oil in bore 116. Engine piston 72 will still move down as described because the total area exposed on the top of engine piston 72 is greater than the effective area at the bottom of engine piston 72 because of the effect of connecting rod 74. Therefore even though the actual pressures are equal, the total force (pressure times area) is greater at the top of the engine piston 72 and it will in fact move downwardly while at the same time displacing power oil from beneath the engine piston, said displaced power oil actually mingling with the power oil above the piston.

Oil from formation 13 in the lower part of pump chamber 69 below the displacement piston 73 is pumped upwardly through the traveling valve passages 79, 81 in the displacement piston 73, the standing valve in the bottom plug 53 of the production unit 42 preventing the formation oil in the pump chamber 69 from passing to the exterior thereof. As displacement piston 73 moves downwardly within pump chamber 69, the formation oil flows via openings 82, 84 into the annular space 51 between the production unit 42 and the tubing extension 15. This pumped oil then flows into the lower end of the macaroni string 19 and is pumped via the same to the surface pipes 29, 32 into the oil-water separator. Near the end of the downstroke, the lower portion 71 of the engine chamber 68 functions as a dash pot and cushions the movement of the engine piston 72.

During the downstroke, the only oil entering macaroni string 19 is a portion of the formation oil that entered the lower end of pump chamber 69 on the previous upstroke. There is no exhaust power oil entering macaroni string 19 on the downstroke.

The following is a description of the valve positioning forces determining the positions of the main valve 101 and pilot valve 103 on the pump downstroke. These forces are derived from the pressure P_1 of the power oil in supply inlet 92 and that pressure P_2 of exhaust power oil and/or pumped oil in macaroni string 19, this latter pressure being the same as that in exhaust power oil passage 91. There is also a pressure P_3 which is less than P_1 by an amount determined by the pressure drop through orifice 137.

For purposes of discussion, the top face or area of the upper end of main valve member 101 can be called A_1 , the top face or exposed area of main valve portion 101a can be called A_2 , and bottom face or area of the main valve member 101 called A_3 . Also, the top face or area of pilot valve member 103 can be called A_4 , and the top face or exposed area of pilot valve piston 134 called A_5 , and the bottom face or area of this piston called A_6 .

The valve positioning forces tending to position the main valve member 101 on the downstroke are products A_1P_1 , A_2P_2 , and A_3P_1 , the first two of these forces opposing the last-mentioned force. Thus, the following relationship exists: $A_1P_1 + A_2P_2 < A_3P_1$, and the main valve member 101 is held in the position shown in Figure 3 on the downstroke.

The valve positioning forces tending to hold pilot valve 103 in the position shown in Figure 3 during a downstroke are the products of A_4P_2 , A_5P_1 , and A_6P_3 , the first two of these forces opposing the last-mentioned force. Thus, the following relationship exists:

$$A_4P_2 + A_5P_1 > A_6P_3$$

When the engine piston 72 reaches the end of its downstroke, fluid can no longer pass through orifice 137 and pressure P_3 becomes equal to pressure P_1 , and the new relationship exists: $A_6P_1 > A_5P_1 + A_4P_2$, therefore, the pilot valve member 103 moves in the other direction, i.e., upward and occupies the position shown in Figure 4. In this position, lateral bores 124 and 125 are no longer in

communication, but rather communication is had via annular groove 126 between bores 123 and 124. As a result, the fluid pressure of the power oil is no longer applied to the lower face of main valve 101. Rather, passages 123, 124, 127 are now in communication with vertical passage 118 and via lateral bores 107 with annular space 117, the latter communicating with the macaroni string 19 via passages 90, 91 and annular space 51.

Now, a new set of forces act on main valve member 101 to position and hold the same in that position shown in Figure 4, the pressure force relationship being

$$A_1P_1 + A_2P_2 > A_3P_2$$

In a similar manner, the pilot valve member 103 will reverse its position at the end of an upstroke and in so doing will reverse the position of the main valve member 101, thus returning the system to the condition shown in Figure 3.

On the upstroke, with the main valve 101 and pilot valve 103 occupying the positions shown in Figure 4, the power oil in annular space 116 flows via openings 88 into the lower end of engine chamber 68, causing engine piston 72 to move upwardly. The upward movement of engine piston 72 is translated by connecting rod 74 to the displacement piston 73 causing its upward movement. As the displacement piston 73 moves upwardly, ball 78 of the traveling valve in piston 73 is seated, and the ball 63 of the standing valve in the lower end of the production unit is unseated, as is the ball 58 of the standing valve in the shoe assembly 18, thereby opening passages 61 and 62. As a result, formation oil which has accumulated in the casing below the production unit flows upwardly into the lower portion of the pump chamber 69. The formation oil in the upper portion of pump chamber 69 is forced out bores 82, 84 into annular space 51 and is pumped up macaroni string 19. Simultaneously, exhaust power oil from the upper end of engine chamber 68 flows via passages 87, 137, 138, 133, annular space 131, passage 132, annular space 122, lateral bores 111, 112, vertical bore 118, lateral bores 107, annular space 117, passages 90, 91, annular space 51, into macaroni string 19.

It is to be noted that on the upstroke, macaroni string 19 conveys both exhaust power oil and formation oil to the surface.

When the engine piston 72 approaches the end of its upstroke, the upper reduced portion 70 of the engine chamber 68 acts as a dash pot, cushioning the upward movement of the engine piston 72 at its upper extremity. When the engine piston 72 reaches the end of its upstroke, the fluid pressures acting on the upper and lower surfaces of the pilot valve piston 134 becomes equal. Then because of the full pressure of the power oil acting on the upper end of pilot valve 103, the latter is forced downwardly to the position shown in Figure 3. As a result, bores 125, 124 are now again in communication via annular groove 126, and the fluid pressure of the power oil is again applied to the lower end of the main valve 101 causing the same to move upwardly and occupy the main valve position shown in Figure 3. On the downstroke, the aforementioned cycle is again repeated.

When it is desired to remove the production unit 42 from the well, valves 24 and 31 are closed, and valves 34 and 37 are opened, power oil thus being pumped by pump 26 via pipes 27, 33, and 29 into macaroni string 19 and exhausted power oil being withdrawn from the well via pipes 23, 36, and 32.

Various modifications and alterations of this invention will become apparent to those skilled in the art from the foregoing discussion and accompanying drawing, and it should be understood that this invention is not limited thereto.

I claim:

1. A fluid pressure actuated reversing valve for use in combination with a fluid actuated, double acting recip-

rocating engine having an engine piston, said reversing valve comprising a directional valve adapted to connect a first side of said engine piston alternately to an exhaust fluid passageway and to both a second side of said engine piston and a source of power fluid, and a pilot valve adapted to change the position of said directional valve, said pilot valve adapted to change positions in accordance with the changes in operating pressure on the opposite sides of said pilot valve whenever said engine piston reaches the end of a power stroke.

2. The apparatus according to claim 1, wherein said directional valve has a small diameter portion and a large diameter portion, said portions defining three faces upon which valve positioning pressures are applied; said pilot valve being adapted to alternately change the pressure applied to one of said faces to cause said directional valve to move from a first to a second position and vice versa.

3. The apparatus according to claim 2, wherein said pressures are power fluid pressure and exhaust fluid pressure.

4. The apparatus according to claim 1, wherein said pilot valve has a small diameter portion and a large diameter portion, said large diameter portion having an orifice therein adapted to permit the passage of said power fluid to said engine for moving said engine piston toward a first position, said orifice also adapted to permit the passage of exhaust power fluid when said engine piston moves in an opposite direction toward a second position.

5. The apparatus according to claim 4, wherein said small and large diameter portions of said pilot valve define first, second, and third faces upon which fluid pressures are adapted to act, said directional valve adapted to alternately permit power fluid pressure and exhaust fluid pressure to act on said first face, said second and third faces adapted to be subjected to the pressures of said power fluid and exhaust fluid modified by a pressure drop across said orifice, said pressures acting on said second and third faces being equal whenever said engine piston reaches the end of a stroke.

6. A fluid pressure actuated reversing valve for use in combination with a fluid actuated engine having an engine piston reciprocally movable within an engine cylinder between first and second positions, said reversing valve comprising: a housing; directional valve means within said housing; pilot valve means within said housing; said directional and pilot valve means each movable between first and second positions; said directional valve means adapted to alternately supply power fluid pressure to first and second sides of said engine piston, said power fluid being supplied via an orifice in said pilot valve means to said first side of said engine piston tending to move the same toward its said first position when said directional and pilot valve means are in their first positions, and said power fluid being supplied to said second side of said engine piston and tending to move said engine piston toward its second position when said directional and pilot valve means are in their second positions; said pilot valve means adapted to cause said directional valve means to move to its first and second positions; said pilot valve means adapted to move to either of its first and second positions in accordance with the cessation of flow through said orifice whenever said engine piston reaches either of its said first and second positions.

7. A fluid pressure actuated reversing valve for use in combination with a fluid actuated engine having an engine piston reciprocally movable within an engine cylinder between first and second positions, said reversing valve comprising: a housing provided with a directional valve cylinder and a pilot valve cylinder; a directional valve reciprocally movable within said directional valve cylinder between first and second positions; a pilot valve

reciprocally moveable within said pilot valve cylinder between first and second positions; a power fluid supply passage system adapted to convey power fluid under pressure; and exhaust power fluid passage system adapted to convey exhaust power fluid under a lesser pressure; said power fluid supply passage system adapted to permit the application of a first valve positioning force on a first end of said directional valve, and to supply said power fluid via a port in said directional valve to said pilot valve chamber and thence through an orifice in said pilot valve to a first end of said engine piston, thereby applying a fluid pressure on the latter and tending to move it toward its said first position; said power fluid supply passage system also adapted to supply via ports in said pilot valve a second greater valve positioning force to a second end of said directional valve tending to maintain the latter in its said first position; said exhaust power passage system adapted to permit the application of a third valve positioning force to an intermediate portion of said directional valve, said exhaust power fluid passage system also adapted to apply via ports in said directional valve a valve positioning force to a first end of said pilot valve which together with a pressure differential across said orifice tends to maintain said pilot valve in its said first position; said pressure differential becoming zero when said engine piston reaches its said first position, whereby said pilot valve is subsequently caused to move toward its second position; said pilot valve in its said second position permitting the release of said second valve positioning force from said second end of said directional valve, and permitting the application of exhaust fluid pressure via ports in said pilot valve to said second end of said directional valve tending to allow the latter to move toward its said second position; said directional valve in its said second position permitting the application of said power fluid pressure to a second and opposite end of said engine piston, thereby causing said engine piston to move toward its said second position and causing exhaust power fluid to be exhausted via said orifice and via a port in said directional valve to said exhaust power fluid passage system; the differential pressure across said orifice again becoming zero when said engine piston reaches its said second position, whereby said pilot valve is subsequently caused to move toward its said first position, and thus causing said directional valve to move toward its said first position, thereby completing a cycle and permitting the repetition thereof.

8. In combination, a fluid actuated, double acting reciprocating engine and a fluid pressure actuated reversing valve, said engine comprising an engine piston recipro-

ly movable within an engine cylinder and a displacement piston reciprocally movable by said engine piston within a displacement cylinder which is adapted to communicate with a source of fluid desired to be pumped, said reversing valve comprising a directional valve adapted to connect a first side of said engine piston alternately to an exhaust fluid passageway and to both a second side of said engine piston and a source of power fluid, and a pilot valve adapted to change the position of said directional valve, said pilot valve adapted to change positions in accordance with the changes in operating pressure on said opposite sides of said engine piston whenever the latter reaches the end of a power stroke.

9. A subsurface hydraulic reciprocating pump adapted to be suspended in a well traversing an oil zone, said pump comprising a fluid actuated reciprocating engine and a fluid pressure actuated reversing valve, said engine comprising an engine piston reciprocally movable within an engine cylinder and a displacement piston reciprocally movable by said engine piston within a displacement cylinder which is adapted to communicate with said oil producing zone, said engine piston adapted to move between first and second positions, said reversing valve comprising a housing; directional valve means within said housing; pilot valve means within said housing; said directional and pilot valve means each movable between first and second positions; said directional valve means adapted to alternately supply power fluid pressure to first and second sides of said engine piston, said power fluid being supplied via an orifice in said pilot valve means to said first side of said engine piston tending to move the same toward its said first position when said directional and pilot valve means are in their first positions, and said power fluid being supplied to said second side of said engine piston and tending to move said engine piston toward its second position when said directional and pilot valve means are in their second positions; said pilot valve means adapted to cause said directional valve means to move to its first and second positions; said pilot valve means adapted to move to either of its first and second positions in accordance with cessation of flow through said orifice whenever said engine piston reaches either of its said first and second positions.
